United States Patent Office

Des. 181,266
Patented Oct. 29, 1957

181,266

COOKING UNIT OR THE LIKE

Octavio Jose Alvarez, New York, N. Y.

Application June 1, 1955, Serial No. 36,318

Term of patent 14 years

(Cl. D81—10)

FIG. 1.

FIG. 2.

Fig. 1 is a front perspective view of the cooking unit; and

Fig. 2 is a rear perspective view thereof.

The unit has substantially the same appearance when viewed from either side.

I claim:

The ornamental design for a cooking unit or the like, as shown and described.
